UNITED STATES PATENT OFFICE.

GUSTAV PETERSON, OF ALTOONA, PENNSYLVANIA.

FURNACE.

1,035,731.

Specification of Letters Patent. Patented Aug. 13, 1912.

Application filed August 28, 1911. Serial No. 646,428.

To all whom it may concern:

Be it known that I, GUSTAV PETERSON, a citizen of the United States, residing at Altoona, in the county of Blair and State of Pennsylvania, have invented certain new and useful Improvements in Furnaces, of which the following is a specification.

This invention relates to furnaces especially designed for the heat treatment of 10 spring steel wherein a high and uniform temperature is necessary for thoroughly heating the steel to make of the same a spring of superior quality, refining the grain of the material which increases the life of the spring, enabling the same to more readily carry the loads for which it is designed and withstand the shocks incidental to the use thereof.

One of the objects of the invention is to 20 provide a furnace in which the material being treated is heated by radiated heat, the material being in a chamber that is entirely surrounded by the heat from the furnace.

Another object is to provide means where- 25 by all parts of the heating chamber have the same degree of high temperature and also to provide means for excluding the cold air from the heating chamber, when the charging door thereof is opened inci- 30 dental to the operation of placing material in the chamber or removing the same there- from.

Still another object of the invention is to provide means whereby the heat from the 35 treating chamber is shunted away from the operator in charge of the furnace.

Another object of this invention is to provide a heat treating chamber wherein the steel treated is not subjected to the usual 40 loss of material, through the formation of scale which is always found when the flames come in direct contact with the steel.

With the above and many other objects in view, which will more readily appear as 45 the nature of the invention is better understood, the same consists of the novel construction, combination and arrangement of parts as will be hereinafter fully illustrated, pointed out, and claimed.

50 In the accompanying drawings—Figure 1 is a top plan view of the improved furnace, shown partly in horizontal section. Fig. 2 is a view in front elevation; shown partly in vertical section. Fig. 3 is a horizontal sectional view taken on the line 3—3, Fig. 2.

Fig. 4 is a vertical sectional view taken on the line 4—4, Fig. 2.

Like reference numerals designate corresponding parts throughout the several figures of the drawings.

The improved heating furnace is prefer- 60 ably formed of heat-resisting bricks and comprises a casing designated by the num- 65 eral 5, equipped with external reinforce- ments which may be T-bars 6, connected by tie rods 7.

Internally the furnace is provided with a heating chamber 8, the bottom being pro- 70 vided with a bed 10, and the top being in the form of an arch 11, the bricks of which are off-set to provide a plurality of rows 75 of staggered openings 12. Access to the chamber 8 is had through the front doorways 13 equipped with vertical guides 14, preferably channel bars, in which the doors 14^a are slidably mounted. The doors 14^a are operated by the counterweighted levers 15, which have link connections 16 there- with.

An arched heat conducting passage 17 80 extends transversely across the top of chamber 8; said passage discharging into a vertical passage 18 that extends down one side of said chamber 8 and communicates with a plurality of parallel lower passages or sub- 85 flues 19 that extend transversely beneath chamber 8 and discharge into a passage 20 leading to a chimney or other outlet 21.

The heat is furnished by burners using a mixture of crude oil and air and include the oil pipes 22 and air pipes 23, each equipped with a controlling valve 24, the air pipes 23 having their nozzles 25 within the nozzles 26 of the oil pipes, and the latter nozzles being within the nozzles 27 of the blast 95 pipes 28. The blast pipes 28 are provided with the regulating shutters 29, and the nozzles 27 of said pipes lie within the inlet ports 30 of the main combustion chamber 30^a which is a part of the conducting pas- 100 sage 17.

Deflecting bridges 31 are arranged so as to separate the combustion chamber 30^a from the heat conducting passage 17 to break up the volume of heat and cause the same to 105 slowly pass through passages 17, 18 and 19, thereby thoroughly heating all parts of the chamber 8 and permitting the heat to pass through openings 12 and heat the top por- 110 tion of said chamber 8 to the same temper-

ature as other parts thereof. The outlet ends of passages 19 are provided with controlling gates 32 having operating levers 33 pivotally connected thereto that extend 5 through openings 34 on one of the walls of casing 5. The openings 34 are reduced at their outer ends and provided with the latching ledges 35 adapted to be engaged by the notches 36 of levers 33 to lock the gates 32 10 in the desired positions. By the employment of the gates 32, one or any number of the passages 19 can be cut off from the chimney passage without interfering with the other passages, and as the operating 15 levers for said gates project through and beyond the exterior of the casing 5, they can be readily manipulated without the necessity of the attendant exposing himself to the heat passing through said passages 19. 20 The main object of these gates 32 is to procure means whereby the temperature of any portion of the furnace can be controlled by forcing the hot gases to flow in any of the desired channels 19; thus balancing the temperature of chamber 8. A steam pipe 37 25 extends transversely across the exterior of the doors 14 and is provided with perforations 38 for discharging steam across the doorway to form a curtain for shielding the attendant from the heat from chamber 8 30 when the doors 14 are opened.

In use the material to be heated is placed in chamber 8, and the heating agent caused to circulate through 17, 18 and 19 so that the said chamber is thoroughly and uniformly heated. The passages 19 that extend beneath the chamber 8 being each equipped with a controlling gate 32, it will be seen that the heat traveling through said passages can be regulated to have a direct communication with the chimney 21 through the passage 19, that is in direct communication therewith, or said passage cut off and the other passages opened, thus causing the heat, 45 or flame, to be divided and pass through all the other passages. By this arrangement, simple and practical means are provided for distributing the flow of heat beneath the chamber 8 to raise or lower the temperature 50 of any portion thereof as may be desired.

Without further description and elaboration it is thought that the many advantages of the herein described furnace are readily apparent and what I desire to cover by Letters Patent is—

1. A furnace for heating metal comprising a furnace casing provided with a chamber for receiving the metal to be heated, said

chamber having a perforate top wall, a heat conducting passage extending over and communicating with the chamber through the perforations in its top wall, sub-flues below the heating chamber, means for closing any selected one of said sub-flues independent of the others, and heating means in communication with the heat conducting passage. 60

2. A furnace for heating metal comprising a casing provided with a chamber for receiving the metal to be heated, said chamber having a perforate top wall and a bottom bed, a heat conducting passage extending over and communicating with the chamber through the perforations in its top wall, a plurality of sub-flues below the heating 70 chamber and in communication with the heat conducting passage, gates in said sub-flues, and heating means in communication with the heat conducting passage. 75

3. A furnace for heating metal comprising a furnace casing provided with a chamber for receiving the metal to be heated, said chamber having a perforate top wall, a heat conducting passage extending over and communicating with the chamber through the perforations in its top wall, a plurality of sub-flues below the chamber arranged side by side and extending transversely of the chamber, said flues also in communication with the heat conducting passage, gates located in each flue and adapted to be operated from the outside of the casing, and heating means in communication with the heat conducting passage. 80

4. A furnace for heating metal comprising a furnace casing provided with a chamber for receiving the metal to be heated, said chamber having a perforate top wall, a heat conducting passage extending over and communicating with the chamber through the perforations in its top wall, sub-flues below the heating chamber, a discharge passage at the terminus of the said sub-flues, gates located in each of the sub-flues and controlling communication between the flues and said discharge passage, a chimney in communication with said discharge passage, and heating means in communication with the heat conducting passage. 95

In testimony whereof I hereunto affix my 100 signature in the presence of two witnesses.

GUSTAV PETERSON.
